UNITED STATES PATENT OFFICE.

WILLIAM E. BARTA, OF ROSLINDALE, MASSACHUSETTS, ASSIGNOR TO BARTA-GRIFFIN COMPANY, OF WORCESTER, MASSACHUSETTS, A CORPORATION OF MASSACHUSETTS.

PRINTER'S COLOR-CARD SYSTEM.

Application filed August 2, 1924. Serial No. 729,714.

This invention aims to provide a printer's color card system for facilitating the comparison of printers' inks of various colors and shades, as they appear when actually printed, the arrangement being such that little handling of the cards is needed, as each color in all its shades is presented to view at one time for inspection and comparison with the others, and if at any time handling becomes necessary and the values of the colors and shades thereby become impaired, the cards so affected may be replaced from time to time, without the necessity of replacing the entire set and the holder therefor.

15

The invention will be best understood by reference to the following description, when taken in connection with the accompanying drawings of one illustrative embodiment thereof, while its scope will be more particularly pointed out in the appended claims.

20

In the drawings:

Fig. 1 is an elevation of a color card system exemplifying the invention, the same being shown as it appears when unfolded for inspection;

25

Fig. 2 is a plan on an enlarged scale showing the card system as it appears when the holder is folded; and

30

Fig. 3 is a detail elevation on the same scale as Fig. 2, illustrating one set of cards of one color, but of different shades.

Referring to the drawings, and to the embodiment of the invention which is selected for exemplification, there is shown a card system comprising a holder 4 having a plurality of sections 5 hinged together, the holder being thereby foldable to protect the cards from the action of light, and from accumulations of foreign matter, which might otherwise impair the value of the cards as standards of comparison. The holder when folded appears as shown in Fig. 2, the sections being so folded that one of them occupies a position between the other two. In this way, the cards are well protected, although when the holder is unfolded, all of the cards are presented to view at one time for comparison.

40

45

50

The holder presents a large number of pockets 6, which overlap one another, and are arranged in horizontal and vertical rows, the vertical rows of each section being separated from each other by vertical strips 7, which project somewhat from the faces of

the pockets. Interference of the parts of one section with those carried by another may be prevented by the provision of other vertical strips 8, having a thickness greater than that of the strips 7, thereby to project 60 a considerable distance beyond the faces of the cards, and to limit the movement of the sections toward one another when folded, as will be evident from an inspection of Fig. 2. The holder may be conveniently 65 made of cardboard, with a paper or cloth covering, and the pockets may be made of cloth for the sake of durability.

Each pocket contains one or more, herein a plurality of cards 9, presenting color 70 standards printed thereon, as by a printed area 10 on each card, exposed on its projecting portion for comparison with the other printed areas of different colors and shades presented by the other cards (see Fig. 3), 75 and in the present embodiment, each card has also printed thereon an identification of its color and shade. In the present example, there are two such identifications, to wit: the name of the color and its shade, as "prim-rose yellow", and also an identification as by number, such as "No. 105". Considering the set of cards shown in Fig. 3, the color yellow is conveniently represented by vertical and horizontal dotted lines crossing each other, in accordance with the chart in the Rules of Practice of the United States Patent Office. Other colors, such as red, blue, brown, orange, black and green, are similarly represented in accordance with said 80 chart. Various shades of each color are distinguished from one another in the drawing by various spacings of the lines representing such color, wide spacing being employed for the lighter shades, and narrower 85 spacing for the darker shades, as will be evident from an examination of Fig. 3, which illustrates primrose, lemon and chrome yellow.

For purposes of ready comparison, the 100 various shades of each color are grouped, as for example, in horizontal rows (see Fig. 1), since by this means, one is better enabled to judge the color and shade more accurately. As before mentioned, each 105 pocket preferably contains more than one card of a given color, and shade, so that if the color value of one card should become impaired, another one can be placed at the front. All of the cards are removable from 110

their pockets, thereby to permit replacement of those whose color values have become impaired, thus avoiding the necessity of replacing the entire set and the holder therefor.

It should be evident from the foregoing that I have provided a simple, convenient, and reliable card system of color standards for use by the printing trade, and that the 10 accuracy of the system may be maintained without undue trouble and expense.

Having thus described one embodiment of the invention, but without limiting myself thereto, what I claim and desire by Letters 15. Patent to secure is:

1. A printer's color card holder, comprising, in combination, a plurality of sections adapted to fold one upon another, each of said sections comprising a plurality of 20 pockets in horizontal and vertical rows, each of said pockets being adapted to contain a

plurality of color cards, vertical separating strips between and separating said vertical rows of pockets, and relatively thick vertical spacing strips at the sides of said sections and projecting therefrom further than 25 said separating strips.

2. In a printer's foldable color card holder, in combination, a plurality of mutually hinged sections, each comprising a plurality of overlapping horizontally aligned pockets of flexible material, vertical retaining strips subdividing said pockets, and additional vertical depth spacing strips 30 adapted for mutual opposition when said sections are in folded position, said spacing strips being deeper from front to back than said retaining strips.

In testimony whereof, I have signed my name to this specification.

WILLIAM E. BARTA.
